(57) CLAIM

I claim the ornamental design for sun glasses with separated visors, as shown and described.

DESCRIPTION

FIG. 1 is a perspective view of sun glasses with separated visors showing my new design;

FIG. 2 is a top plan view thereof;

FIG. 3 is a front elevational view thereof;

FIG. 4 is a left side elevational view thereof, the right side elevational view thereof being a mirror image thereof;

FIG. 5 is a rear elevational view thereof; and,

FIG. 6 is a bottom plan view thereof.
